UNITED STATES PATENT OFFICE

159,724

GOBLET

Marvin Glass, Chicago, Ill.

Application September 4, 1948, Serial No. 148,469

Term of patent 14 years

(Cl. D36—8)

To all whom it may concern:

Be it known that I, Marvin Glass, a citizen of the United States of America, residing at Chicago, in the State of Illinois, have invented a new, original, and ornamental Design for a Goblet, of which the following is a specification, reference being had to the accompanying drawing, forming a part hereof.

In the drawing:

Fig. 1 is a perspective view of the goblet showing my new design.

Fig. 2 is a sectional view of same.

I claim:

The ornamental design for a goblet, as shown.

MARVIN GLASS.
